No. 37,390.

Patented April 4, 1905.

UNITED STATES PATENT OFFICE.

CHARLES F. NUEZEL, OF CINCINNATI, OHIO.

DESIGN FOR A COAT AND HAT HOOK.

SPECIFICATION forming part of Design No. 37,390, dated April 4, 1905.

Application filed February 23, 1905. Serial No. 247,046. Term of patent 3½ years.

To all whom it may concern:

Be it known that I, CHARLES F. NUEZEL, a citizen of the United States, residing at Cincinnati, Hamilton county, State of Ohio, have invented a certain new, original, and ornamental Design for Coat and Hat Hooks, reference being had to the accompanying drawings, which show my design.

I claim—

The ornamental design for a coat and hat hook, as shown.

CHARLES F. NUEZEL.
